UNITED STATES PATENT OFFICE

ASHUR U. WETHERBEE, OF EVANSTON, ILLINOIS, ASSIGNOR TO AUTOGAS CORPORATION, OF CHICAGO, ILLINOIS, A CORPORATION OF DELAWARE

COMBUSTION CHAMBER

Application filed November 19, 1931. Serial No. 576,076.

This invention relates to improvements in gas burning appliances and more particularly to a gas burner suitable for use in heating systems originally designed for burning solid or liquid fuels and constitutes an improvement upon the burner illustrated in my pending application Serial No. 493,537 filed November 5, 1930.

The principal objects of the present invention are the same as those of my previous invention just mentioned with the addition of the following.

An object is to provide a new and improved combustion chamber comprising a series of interlocking refractory elements constituting a combustion chamber adapted for installation in heating systems originally designed for the burning of solid or liquid fuels.

Another object of the invention is to provide a combustion chamber or conversion burner for installation in heating systems or furnaces and in which none of the refractory elements of said chamber contact with the interior walls of the firepots of said systems.

A further object is to provide a combustion chamber composed of a plurality of interlocking refractory elements designed to permit expansion and contraction thereof without disturbing the inter-relationship between said elements.

A still further object is to provide a new and improved form of radiant elements.

An additional object is to provide a combustion chamber having a base ring constructionally arranged for the super-position of a plurality of refractory elements thereon which interlock therewith and between which a series of narrow slots are provided for the exit of the gases of combustion.

An additional object of the invention is to provide a refractory combustion chamber composed of a series of elements of refractory material defining a combustion chamber and a top cover therefor which projects beyond the exterior surfaces of said combustion chamber.

Another important object of the invention is to simplify the construction of a refractory combustion chamber by building it up of separate elements of ceramic material or the like, preferably in the general manner of a log cabin whereby the end of each element serves to separate two adjacent elements and form an elongated aperture therebetween.

Whether or not arranged in just this man-

ner, I consider it very desirable that these separate elements be arranged in vertical rows, each row forming one side of the combustion chamber, and preferably with spaces between adjacent elements in each row.

Additional objects and advantages will be apparent from the following description of an embodiment of the invention.

In general the present invention operates on the same principles as the one forming the subject of the aforementioned application, but owing to a more advantageous construction of the refractory elements an improved result in operation as well as a more durable construction are achieved.

In the present invention the combustion chamber comprises an annular ring with superimposed interlocking sectors forming a base for a plurality of superimposed refractory elements arranged in interlocking relationship, preferably built up like a log cabin or otherwise arranged in vertical rows as described above, and which permit of expansion and contraction of said elements without distortion or rupture of the same. The tops of the sectors are preferably formed with depressed portions extending part way along the surface thereof and into which the first row of refractory elements are adapted to fit and interlock with said portions. When the refractory segments have been laid up in position they form a stack of approximately cylindrical proportions containing the maximum amount of surface for securing surface catalysis and the interstices or slots between the respective elements are proportioned to permit the products of combustion to escape from the inside to the outside of the cylinder such that a maximum amount of radiant energy is emitted from the refractory elements.

In the drawings which represent an exemplary embodiment of the invention and wherein like reference characters designate like parts,

Fig. 1 is an isometric view, partly in section, illustrating the preferred construction of the combustion chamber of the invention.

Fig. 2 is a view of the base sectors in assembled position with a plurality of radiant elements and the top or cover disposed thereabove illustrating one method of assembling the parts.

Fig. 3 is a plan view of a row of the refractory elements in assembled position.

Fig. 4 is a top, Fig. 5 a front and Fig. 6 a bottom view of one of the refractory elements.

Fig. 7 is a sectional view thru two of the radiant elements as if taken on the line 7—7 of Fig. 4, illustrating the relative positions of the radiant elements when in assembled position.

Figure 8 is a perspective view of a modified arrangement and form of refractory members.

In the exemplary embodiment of the invention the casing 10 is of such size and configuration as to be projected thru the ashpit door of a furnace or heating system and is provided with an opening 11 therein over which the combustion or burner chamber is assembled. The casing at its exterior end is provided with suitable connections and controls as required for the efficient operation of the system. Enclosed within the casing is a mixing tube 12 thru which the primary combustible mixture is supplied to the burner element 13 which has a deflector cap 14 for directing the mixture and secondary air outwardly into proximity to the walls of the combustion chamber.

These devices as substantially described are shown in my copending application here-
20 tofore referred to and their operation is therein fully set forth. I do not, therefore, intend to claim them herein insofar as they are claimed in that application, and for a more full explanation of their operation than is obvious from the description herein given, reference is made to said application.

The base section of the combustion chamber may be and is preferably made up of a series of separable elements to facilitate manufacture and assembly of the construction and generally comprises a ring 15, substantially triangular in cross section, with the interior face or side thereof hollowed out in a somewhat bowl-shaped manner as illustrated. Superimposed on this bowl-shaped ring are three sectors 16 interlocking with each other and with the base ring to form an essentially tight chamber. The interlocking relationship may be accomplished in various ways and may be in the form of a lapped joint 17 between the sectors and between the sectors and the ring 15.

With the interlocking feature between the sectors and between the sectors and ring a substantially tight cylinder is formed for retaining the gases during the preliminary stages of their combustion and the construction is such as to allow for a free expansion and contraction of the elements when subjected to the intense heat of the burning gases. The ring and the sectors may be retained in position by any suitable means, such as a band 18, which, while retaining the elements in position, permits expansion and contraction thereof.

The upper portions 19 of the sectors are extended, as well as depressed, to form a recess in which the first segments, to be later described, are adapted to repose. The end walls of the recesses are coterminous with the tops 70 of the sectors and are notched at 21 for cooperation with the end portions of segments to support the segments in spaced relation to said portion so as to leave a small narrow orifice or slot therebetween corresponding to the 75 slot between successive superimposed segments. The special arrangement of the depressions and extensions is such that they support the first three segments in such position that the addition of three more segments 80 will form a hexagon. Although it is to be understood that while the sectors are formed for the reception of segments which form a hexagon when assembled thereon, the invention is not limited to this construction but 85 may be varied for a greater or lesser number of segments. The ring, sectors, and segments are preferably composed of ceramic or refractory material capable of withstanding the intense heat to which they are subjected, 90 said materials being well known in the art.

The segments 22 may take any desired form but preferably comprise an elongated body portion 23 provided with a shoulder or flange 24 adjacent the ends thereof. The bottom 95 portion 25 of which extends slightly below the bottom face of the body. Protruding from each shoulder and generally axially to the direction of the body portion is a web or neck 26 which terminates in a head 27 at its 100 distal end. In elevation this web or neck is preferably slightly greater than half the thickness of the body portion of the segments and is slightly inclined outwardly from the axis of the body portion as illustrated in Fig. 4, so that the continuous supporting column consisting of these superposed webs, shall obscure as little as possible of the radiation from the incandescent interior surface 105 of the combustion chamber. The neck or 110 web is proportioned so that when the ends of the segments are stacked together, as illustrated in Fig. 1, generally in the manner of a log cabin, or otherwise arranged in vertical rows to form a multi-sided cylinder, they will 115 form a solid support for one another and at the same time separate the segments so that there will be a narrow slot left therebetween. The web is preferably disposed intermediate 120 the top and bottom of the segment, and the top of the head 27, the top of the shoulder 24, and the top of the ridges 31 are preferably all in the same plane, to facilitate the manufacture of these segments without twisting or warping. The distance between the shoulder 125 24 and the head 27 is slightly greater than the width of the neck itself so that when the succeeding segments are placed upon the underlying segments they can all move to a sufficient degree to allow for contraction and 130

expansion of the pieces without putting any undue strain upon themselves while at the same time being prevented by these respective shoulders and heads from moving out of their fundamental interlocking position.

The body portions 23 of the segments are preferably, though not necessarily, trapezoidal or triangular in cross section as illustrated in Fig. 7 and are so arranged that the outer face 28 is of greater dimensions or height than the inner face 29, while the lower face 30 is inclined downwardly and outwardly as illustrated. The top and sides of the body portion are preferably provided with grooves or ridges 31, those on the top extending generally longitudinally of the body, while those on sides extend in a generally vertical direction. The object of these grooves is to increase the surface area of the segments and thereby increase the amount of surface catalysis and thereby secure the complete combustion of the last molecules of the combustible gases, or in other words, to obtain products of combustion entirely free of carbon monoxide with the minimum amount of excess air. In addition to providing this extended surface, these grooves and ridges also create a certain amount of turbulence in the gases flowing thereover, thereby assisting in bringing the molecules of combustible gases in contact with the molecules of oxygen without having a material surplus of these molecules of oxygen. They also add to the amount of radiating surface.

35 The lower face 30 of the body of the segments, which forms the upper portion of the slots between adjacent segments when in assembled position for the issuance of the gases, is covered with a series of sharp conical or pyramidal projections 32. These projections serve the purpose of extending this surface, of creating a turbulence in the gases as described above, and also due to the intimate contact with the gases, of reaching a radiant temperature sooner than the principle mass of refractories and thereby sooner introducing the element of surface catalysis when the burner is first put in operation. These projections also serve to increase the amount of radiant heat emanating from each of the slots and thereby adding materially to the maximum transfer of heat by radiation.

Intermediate the ends and extending downwardly from the lower face 30 of the segment, 55 is a leg or member 33, the lower face of which is coterminous with the lower face of the shoulders 25. When the segments are in assembled position, the lower faces of the shoulder 25 and member 33 are slightly spaced from the top of the subjacent segment as illustrated in Fig. 7, thus, as long as the segment is intact the weight thereof is supported by the neck or web portion 26 which rests upon the web of the sub-adjacent segment. However, 60 should the segment for any reason break or

rupture such broken part would only drop or sag a very short distance at the point of rupture when either the shoulder or leg would immediately contact with the underlying segment which would then carry the weight of the broken end of the segment, the drop or displacement of the segment being so slight that it in no way disturbs what is in effect a continuous supporting column consisting of all the ends of all the segments at the corner where they overlap. This construction increases materially the effective length of service of the stack of refractories and reduces replacement very greatly.

After the ring 15 and sectors 16 have been assembled segments 22 are placed in each of the depressions 19 as illustrated in Fig. 1, after which the remaining segments are placed in position with the ends overlapping as illustrated in Fig. 3. Successive rows or tiers of the segments are placed in position until the cylinder has been built up to the desired height, which may vary in accordance with the type of furnace or boiler with which the burner is to be used. When the combustion chamber or cylinder is built up in the manner just described a series of long narrow slots are formed between the segments and the sectors and between the respective tiers or rows of segments. These slots or openings are preferably of smaller height at the outside than at the inside, this being obtained by the downward slope or inclination of the bottom or lower face 30 of each of the segments. This downward slope of the lower face 30 tends to restrict too free movement of the gases thru the slots and at the same time, since it is turning the gases downward where-as such gases tends to rise, it creates an additional turbulence in the gases to secure an intimate mixture between the particles of the gases and the oxygen necessary for their combustion. By virtue of the similarity of construction of the respective segments the slots or openings between the respective segments are substantially uniform throughout the combustion chamber. This uniformity of the outlet openings, for the escape of the gases, contributes to a uniform distribution of escape of the gases from the combustion chamber thereby materially increasing the efficiency of the burner to a very high degree, since the segments are brought to a condition of equal incandescence at substantially the same time, thus attaining a greater surface for the emanation of radiant heat than would otherwise be attained.

Radiant heat emanation from the interior surfaces of the combustion chamber pass outwardly thru the converging slots to a greater degree than would otherwise be attained by a slot of uniform dimension from the interior to the exterior of the combustion chamber. The angle of divergence between the top and bottom faces of the slot is preferably great

65 130

enough so that these surfaces projected across the projected surfaces of the adjacent slots above and below, so that in effect none of the interior vertical surfaces are obscured from radiating heat directly to the boiler or furnace walls through the slots.

The top of the combustion chamber is closed by a cover 34 preferably made in two pieces to facilitate its insertion thru the openings in the boiler or furnace. When the segments are laid up or assembled in a fashion similar to that of a log cabin there will always be half as many open sections or spaces at the top as there are segments in the cylinder or combustion chamber. In other words, with a perfectly flat cover there would be a number of extra wide slots which would allow an excessive amount of such gases to escape thru those slots. To overcome this or to reduce the slots to approximately the same dimensions as that of the slots between intermediate segments the top is provided with bars or projections 35 so located that they fit into the spaces between the topmost segments and reduce those spaces to substantially the same size as the slots between adjacent segments. These bars 35 also interlock with the segments and prevent displacement of the cover.

If desired, the top or cover may be made circular and of slightly greater diameter than the stack or combustion chamber so as to slightly overhang the same. This overhanging or projecting portion of the cover serves to baffle the escaping gases causing them to scour or scrub the sides of the firepot in which the combustion chamber is located. This baffling action also tends to retain the hot gases within the firepot thereby causing them to give off an additional amount of heat directly to the firepot wall.

Another possible form of the invention is illustrated in Figure 8, wherein rods 57 of refractory material are placed together to form what may be termed a "log cabin" type of combustion chamber. In this form of the invention, the general shape of the slots are such that the wider portions thereof are directed inwardly and that they converge outwardly to form slots 58 between adjacent rods 57. The ends of the rods are shaped as at 59, to fit the ends of adjacent rods so that, when they are assembled, they interlock with each other to form a rigid unit. While the rods are shown as substantially circular in cross-section, they may be triangular, rhombic, or any other form.

It is to be understood that I do not wish to be limited by the exact embodiments of the device shown, which are merely by way of illustration and not limitation, as various and other forms of the invention will of course be apparent to those skilled in the art without departure from the spirit of the invention or the scope of the appended claims.

Part of the subject-matter herein claimed is

continued from my said prior application No. 493,537, filed November 5, 1939, and to this subject-matter the present application is a continuation in part of said application No. 493,537. It is not my intention to claim in the present application any subject-matter claimed in said application No. 493,537 or in my prior application No. 207,399, filed July 21, 1927 and which latter application has become Patent No. 1,898,799, Feb. 21, 1933.

I claim:

1. A combustion chamber comprising a base section, a plurality of separate ceramic segments superimposed on said base and arranged in vertical rows each of which rows forms one side of said chamber, said segments having spacing means forming intervening slots, between adjacent elements of each row, and a cover for the chamber formed thereby.

2. A combustion chamber comprising a base section, a plurality of segments of ceramic material superimposed on said base with the ends thereof in interlocking relation to form the vertical sides of said chamber, and arranged to form long narrow slots between adjacent superimposed segments and a cover superimposed on said segments.

3. A combustion chamber comprising a base section having its top arranged for the reception of segments, a plurality of segments spaced around the top of said base and coacting therewith and additional segments built up on said first named segments generally like a log cabin with the ends overlapping and with spaces between the vertically superimposed segments and forming a combustion chamber approximately polygonal in plan view, said segments being laid up in the form of a stack and a cover for the top of said stack.

4. A combustion chamber comprising a base section provided with spaced depressed portions on its top, segments of ceramic material located in said depressed portion and a plurality of other segments laid up in successive layers to form a stack, the ends of one layer interlocking with the ends of the adjacent layer to form a multisided chamber with long narrow slots between adjacent segments and a cover superimposed on the last row layer of segments.

5. A combustion chamber comprising a plurality of interlocking sectors forming a base, a plurality of segments of ceramic material spaced around the top of said sectors and additional segments, the ends of which interlock with the ends of adjacent segments laid up in tiers to form a stack and a cover superimposed on the last row of segments.

6. A combustion chamber comprising an annular ring of bowl shaped formation on its interior, a plurality of sectors superimposed on and interlocking with said ring and with each other, each of said sectors having a depressed portion, a segment of ceramic

material disposed in each of said depressed portions and other segments overlapping and coacting with the adjacent ends of the first named segments, and arranged in staggered layers one above the other to form a chamber. 7. A combustion chamber comprising an annular ring of bowl shaped formation on its interior, a plurality of sectors superimposed thereon and interlocking therewith and with each other, radiant elements disposed on each of said sectors, other radiant elements overlapping and resting on the first named segments and forming a stack, there being openings between adjacent segments, for the escape of the products of combustion from the interior of said stack and a cover superimposed on said stack.

8. A combustion chamber comprising a base ring having a bowl shaped interior portion, three sectors superimposed on said ring and interlocking therewith and with each other, a radiant element disposed on each sector and spaced therefrom to provide an opening therebetween, other radiant elements disposed between adjacent ends of the first named elements and resting thereon and interlocking therewith and successive rows of radiant elements superimposed on said adjacent elements and forming a stack, the arrangement being such that elongated openings are formed between each element for the escape of the products of combustion from the interior of said chamber.

9. A combustion chamber comprising a base section and a plurality of radiant elements superimposed thereon in layers and arranged in staggered relation with intervening slots between adjacent superimposed elements, said elements overlapping at the end portions thereof which overlapping portions form a column of contiguous end members from the bottom to the top and a cover for the top of said chamber.

10. A combustion chamber comprising a stack formed of a series of superimposed segments arranged in layers with the adjacent ends of the segments overlapping and interlocking with each other and arranged such that there is an intervening slot between adjacent superimposed segments for the escape of the gases of combustion from the interior of said chamber.

11. A combustion chamber comprising a stack of radiant elements arranged in staggered layers, the contiguous ends of the segments interlocking with each other to thus form a narrow slot like passage between adjacent superimposed segments.

12. A combustion chamber comprising a stack built up of elongated segments arranged in layers and each of which segments is provided with a neck at each end thereof, said segments being built up to form the vertical walls of said chamber, and each of which necks overlaps and interlocks with the necks

of contiguous segments, the neck being of sufficient thickness to form a slot between adjacent superimposed segments, and a cover for said stack, said cover being provided with extensions which lie between the ends of the top-most layer of segments to provide slots between each said extension and the subjacent segment.

13. A combustion chamber comprising a base section having spaced depressed portions in the top thereof, an elongated radiant element in each depressed portion and provided with ends interlocking with the contiguous portion of the base section, other radiant elements superimposed between and on the ends of the first named segments and interlocking therewith, successive segments placed between the ends of the second named segments and forming a stack with elongated slit like openings between adjacent superimposed segments for the escape of the gases of combustion from the interior of the chamber and a top for such stack provided with extending portions fitting between the ends of the last layer of segments to provide a slot between each portion and the subjacent segment of substantially the same dimensions as the slot between adjacent layers of segments.

14. A combustion chamber comprising a base portion and a plurality of elongated elements superimposed thereon and arranged in staggered relation to form a stack, each segment comprising a body portion and a neck at each end thereof for cooperation with and overlapping with the neck of the adjacent element, the overlapping portions forming a continuous support for supporting the elements from the base portion and providing a narrow slot between adjacent layers of segments, the bottom portion of each segment declining outwardly and downwardly and provided with a series of protuberances which become incandescent from the heat of the gases passing thru the slot and a top for said stack extending beyond the periphery of said stack.

15. A radiant element comprising an elongated strip of radiant material substantially trapezoidal in cross section and having reduced neck portions at each end thereof.

16. A radiant element comprising an elongated member of ceramic material, the top and sides of which are provided with grooves and ridges and the under side of which is provided with knob like projections and having angularly disposed neck portions at each end thereof.

17. A radiant element comprising an elongated body portion provided with ridges and grooves on the top and sides thereof and having knob like projections on the under side, said body provided with shoulders at the ends thereof and angularly disposed neck portions projecting from said shoulders.

18. A radiant element for use in a combustion chamber.

- tion chamber comprising an elongated body portion substantially trapezoidal in cross section with the lower side thereof angularly disposed with reference to the upper side, said body portion provided with shoulders angularly disposed with reference to the axis of the body and neck portions projecting from said shoulders and substantially at right angles thereto.
19. A radiant element for use in a combustion chamber comprising an elongated body portion substantially trapezoidal in cross section and with the lower face thereof angularly disposed with reference to the top, said body having shoulders at the ends thereof, the tops of which are coterminous with the top of the body portion and the bottoms of which projects slightly beyond the lower edge of the body portion, neck portions projecting from said shoulders and arranged at an angle to the body portion, and a head at the distal end of each neck portion.
20. A radiant element for use in a combustion chamber, comprising an elongated body portion substantially triangular in cross section and terminating in shoulders at the ends thereof, the lower edges of which project slightly beyond the lower edge of the body, a leg intermediate said shoulders, the lower edge of which is coterminous with the bottoms of said shoulders, neck portions projecting from each shoulder and arranged at an angle to the axis of the body and a head at the distal ends thereof.
21. A gas burner comprising, in combination with a heater having a firebox and an ashpit of a gas burner comprising an elongated box structure extending through said opening and provided with a burner arranged on its upper side substantially at the center of the bottom of the firebox and containing means for supplying gas and air to said burner and in combination with a burner structure of refractory material supported wholly by said box structure over said burner and spaced a substantial distance from the inside of the firebox and constructed and arranged to be heated to incandescence by said burner and to supply heat to the wall of the firebox by radiation in a manner simulating the heating thereof by incandescent coal, said burner structure having a hollow body portion built up generally like a log cabin of separate elements the end of each of which separates two of the other elements to provide an elongated slitlike aperture between them, together with a cover over the top of and supported by said body portion.
22. A gas burner comprising, in combination with a heater having a firebox and an ashpit with a side opening, of a gas burner comprising a box structure arranged in said
- ashpit and provided with a burner arranged on its upper side substantially at the center of the bottom of the firebox and having means for supplying gas and air to said burner from outside the heater, and in combination with a burner structure of refractory material supported wholly by the inner end of said box structure over said burner and spaced a substantial distance from the inside of the firebox and constructed and arranged to be heated to incandescence by said burner and to supply heat to the wall of the firebox by radiation in a manner simulating the heating thereof by incandescent coal, said burner structure having a hollow body portion built up generally like a log cabin of separate elements the end of each of which separates two of the other elements to provide an elongated slitlike aperture between them, together with a cover over the top of and supported by said body portion.
23. A gas burner comprising, in combination with a heater having a firebox and an ashpit with a side opening, of a gas burner comprising a box structure arranged in said ashpit and provided with a burner arranged on its upper side substantially at the center of the bottom of the firebox and having means for supplying gas and air to said burner from outside the heater and in combination with a burner structure of refractory material supported wholly by the inner end of said box structure over said burner and spaced a substantial distance from the inside of the firebox and constructed and arranged to be heated to incandescence by said burner and to supply heat to the wall of the firebox by radiation in a manner simulating the heating thereof by incandescent coal, said burner structure having a hollow body portion built up generally like a log cabin of separate elements the end of each of which separates two of the other elements to provide an elongated slitlike aperture between them, together with a cover over the top of and supported by said body portion.
24. A hollow burner structure built up of separate refractory elements the end of each of which separates two of the others and which have spacing portions and intervening thinner portions to provide an elongated aperture between them.
25. A hollow burner structure built up generally like a log cabin of separate refractory elements the end of each of which separates two of the others to provide an elongated aperture between them, together with a refractory top supported by said structure.
26. An element of ceramic material for a burner structure having reduced-size flattened ends each of which is adapted to be seated between the correspondingly-formed ends of two similar elements.

ASHUR U. WETHERBEE.
